METHOD AND APPARATUS FOR WINDING COILS

Charles Philippe Boucher, Jersey City, N. J., assignor to Boucher Inventions, Limited, a corporation of Delaware

Application August 16, 1937, Serial No. 159,407

13 Claims. (Cl. 242—10)

My invention relates to high voltage and/or high frequency electrical apparatus and more particularly to induction coils employed in such apparatus, and to an art of producing the same.

One of the objects of my invention is the production in a simple, direct and economical manner of high voltage and/or high frequency induction coils which are particularly adapted to withstand the many varying conditions encountered in actual practical use.

Another object is the provision of an induction coil which is compact, strong and rugged, which inherently possesses a minimum leakage reactance, which provides excellent elimination of heat under operating conditions, and which is peculiarly free from bursting or leaking under the severe conditions encountered in high voltage and high frequency apparatus.

Still another object of my invention is the provision of apparatus for manufacture of coils of the type described, which is rugged in construction and which is simple, efficient and economical in operation.

Other objects in part will be obvious and in part pointed out hereinafter.

The invention accordingly consists in the combination of elements, features of construction and arrangement of parts and in the several steps and the relation of each of the same to one or more of the others as described herein, the scope of the application of which is set forth in the following claims.

In the accompanying drawing illustrating certain features of my invention:

Figure 1 represents a side elevation view of my apparatus, certain portions being shown in section to more clearly disclose certain features of the invention.

Figure 2 is a cross sectional view of the apparatus shown in Figure 1 as seen along the line 2—2 of that figure.

Figures 3 and 4 illustrate certain modified forms of my coil-winding apparatus as seen in vertical section, and

Figure 5 represents a detached view, on an enlarged scale, of a coil-winding form as used in the apparatus of any one of Figures 1, 3 and 4.

Like reference characters denote like parts throughout the several views of the drawing.

As conducive to a clearer understanding of certain features of my invention, it may be noted at this point that in low-voltage electrical apparatus, say 1000 volts or under, and at commercial frequencies, say 60 cycles, the induction coils employed in such apparatus can be so designed

mechanically by ordinary manufacture that the coil dimensions are not excessive, and these coils give good results.

In high power electrical apparatus where heavy currents are encountered and the coils are formed of heavy gauge wire, such as No. 10 wire or larger, it is the usual practice to submerge the coils in oil. This effectively eliminates excessive heating. In addition, the freely flowing oil prevents the formation of gas and air pockets around the coils. High frequency discharges are substantially eliminated in such apparatus. Any coil discharges are of such short duration that they represent no source of danger. Thus, in electrical apparatus employing coils operated in oil, satisfactory performance at high voltage is readily obtained. Such apparatus, however, is exceedingly bulky and expensive.

In the rapidly developing modern fields of electrical activity, where electrical apparatus of only moderate current ratings are employed, such for example as voltage regulators, high voltage luminous tube supply (the conventional neon tube), the high voltage supply for X-ray machines, automobile ignition coils, and the like, the high voltage current employed often is also of high frequency, say upwards of many thousands of cycles per second. The nature of the equipment is such as not to warrant oil as an insulating medium. Here disturbing factors, such as, local generation of heat, local capacitance, electrical leakage, particularly at the sides or margins of the coils, chemical effects, high frequency discharges, and the like, all or a part of which are encountered in present day practice, must be minimized to the point of being negligible, in order to ensure long and satisfactory operation of the coil. Experience has shown that it is these factors, substantially in the order named, which result in premature failure of coils operated at high voltages and/or high frequencies.

According to accepted practice, induction coils are wound dry, as by means of a machine. When completed, the coils comprise a hollow core, conveniently of paper or other fibrous material, on which are superposed successive and alternate layers of fine wire and paper.

Thereafter, following one conventional method, the coils are first heated and then placed in a vacuum tank carrying an appreciable vacuum head, whereupon a hot, molten insulating compound is introduced, filling the coils by capillarity. Thereupon positive pressure is applied, all voids of the coil then supposedly being filled

with the compound. The coils are withdrawn and allowed to cool. As a practical matter, when this method is employed, it is impossible, regardless of the degree of vacuum, amount of pressure, or type of insulating compound used, to rid the coils completely of moisture, and free spaces unfilled with compound, are left in the coils.

In a second conventional method the coils, after being air-heated to dryness, are placed on forms which tightly grip the coils about their entire periphery. After the coils, thus gripped, are placed horizontally, molten insulating compound is poured on the upper parts of the coils and is allowed to pass downwardly through the coils by gravity, driving away the gases and moisture ahead of it. After a predetermined length of time, pouring is stopped and the coils are permitted to cool, ready for use. While this method is found to produce, in comparison with the method first described, better coils with fewer gas pockets, still by no means all of the pockets are eliminated, and many pockets are left.

In a third method, the coils, after being wound, are dipped into insulation varnish or compound, which may be either hot or cold. The coils are then heated to harden the compound, whereupon, after cooling, they are ready for use. In this case, the entire center of the coil retains gases and moisture, and the coil is subject to unexpected failure under high voltage and/or high frequency conditions.

The prior art coils when subjected to high voltage and/or high frequency service fail because local high voltage discharge occurs wherever air spaces are found within the coil. The discharge usually begins with a so-called corona or brush discharge. Heating results, which may be accompanied by charring of insulation and the short-circuiting of adjacent turns or successive layers of the coil. Since the breakdown phenomenon is aggravated as the discharge space becomes larger, the coil soon goes out of operation. Furthermore the layers of coil winding serve as condensers, and taken in conjunction with the inductance of the coil, may set up an oscillating condition giving rise to voltages which will break down an air pocket giving sparking between layers. Since air pockets initially contain oxygen, the high voltage discharge converts the oxygen into ozone, which, under the action of the local heat generated by the discharge, expands and forces its way out of the coil, thus destroying the insulation at the surface of the coil. In addition, chemical attack of the conducting wire is frequently encountered, due to the powerful oxidizing action of the ozone.

Difficulty is also occasioned, when ordinary methods of winding in air and subsequent impregnation are used with temperatures but little above the boiling point of water, say about 220°, due to the fact that all moisture remaining in the coils in the form of water vapor, not being driven off inasmuch as a perfect vacuum cannot be obtained in air, is trapped in the coils as soon as the compound is thereafter applied, and is condensed when the coil cools. As a rule this condensation occurs in the air pockets. Now, when heat is generated in these pockets in the manner fully pointed out hereinbefore, the local temperature in the neighborhood of the pockets rises to about 400° F. or higher. At these temperatures the water vapor creates a pressure sufficient at times to break the turns of the coil. Particularly in the case of transformers, using coils of this

type, which are filled with compound having little elasticity, either the coils yield under the stress thus applied or else the movement of the coils fractures the compound, producing the detrimental phenomenon known as breathing, that is, the admission of outside air into the compound through the cracks which are formed.

Again, it is common practice, in coils used for neon, X-ray, or other high frequency transformers, to provide what is known as a sparking margin, that is, a space of from one sixteenth to one-quarter of an inch between the edge of the paper or other insulation, and the first and last turns of the layer of wire placed adjacent thereto. This spacing serves to prevent leakage and sparking and provides in coils intended to operate at say 2000 volts or more, one of the best factors of safety for the coil. Now, when a coil is machine-wound, it is practically impossible to ensure that the corresponding edges of the layers of insulation are flush. Where unevenness is had pockets are formed. In addition, these edges frequently contact each other, forming closed pockets which are not penetrated by the compound during the subsequent treatment. Where pockets are formed gases and moisture are trapped therein. In subsequent use electrical leaks become frequent, and after a time the coils tend to fail due to heat and chemical action on the conductors.

An object of my invention, therefore, is to eliminate the above-mentioned difficulties found in coils of the prior art, and to produce a coil which is compact and closely wound, which is free from air-pockets, gas and moisture both between layers of windings and between coil edges or margins, and which is of low leakage reactance and high heat-dissipating efficiency. Another object is to provide a simple, practical and efficient method and apparatus for economically producing such a coil.

Referring now more particularly to the practice of my invention, attention is directed to Figures 1 and 2. A container 1, preferably formed of metal, is provided of any desired shape, shown as cylindrical, with rounded, substantially semi-spherical bottom 2. The container 1 is adapted to be filled to a convenient level 3 with a suitable insulating and impregnating material, indicated generally by the reference numeral 4, such for example as rosin, paraffin, wax, insulating varnish, or the like. The compound preferably is of such character as to be either plastic or solid at room temperature with a melting or fusing point somewhat above the boiling point of water. The melting-point, of course, is below that at which paper will char. A convenient melting-point range for the usual conditions of practice is roughly, 230°-350° F. The surface of the compound preferably is maintained freely open to the atmosphere. All moisture present in the compound thus will be vaporized and eliminated from the system, since the temperature is sufficient to vaporize moisture even at the pressure existing at the lower part of the container.

To maintain the compound in the container at a desired temperature, suitable conventional heating means are provided. While these heating means are shown in Fig. 1 as comprising electric elements 5-5, it is at once evident that where desired, the heating can be accomplished by steam, or hot gas jackets and the like.

A winding machine is employed in connection with the container 1, certain portions of this ma-

chine being illustrated in Fig. 1. On a shaft or arbor 6 a winding form 7 is mounted by any suitable means, such as a spider 8. The form 7 is intended to be rotated in the direction of the arrow shown on the coil 9, which is in the process of construction. The coil 9 is wound on a core tube 7a, fitted on the form 7.

Conducting wire 10 is led from a suitable source, not shown, across conventional guide means, such for example as the schematically illustrated guide sheave 11 and bracket 12, to the winding form 7. The temperature of the impregnating compound 4, the linear rate of feeding the wire 10, and the location of form 7 below the level of the compound all are so selected and correlated that between the time that the wire 10 enters the compound 4 and the time that it reaches the form 7, it will be substantially entirely freed of all traces of moisture, the moisture, quickly vaporized, passing freely upwardly to the surface 3 of the compound, where it escapes, even when the temperature of the compound 4 is but little in excess of the boiling point of water. For plain enamel-covered wire, good results are had where the form is located, for example, at least one inch, and preferably several inches, beneath the surface of the compound, it being understood that the depth to which the wire extends is appreciably in excess of this figure.

The wire 10, which usually is of small gauge, say No. 26 or under, is wound round form 7 until a complete layer is built up. At this time a layer of flexible sheet insulation, such as paper or the like, is introduced to serve the combined purpose of a spacer and an insulator between adjacent layers of conducting wire.

For reasons pointed out hereinbefore, it is essential that all moisture and entrapped gases be removed from this insulation before it is wound on the form, particularly to prevent local condenser action, and mechanical expansion of gases and water vapor, as well as chemical action of the gases. Now, considerable practical difficulty is encountered in removing bubbles of gases entrapped on the insulation because of the fibrous nature of the latter, presenting a large number of minute interstices and crevices from which it is difficult to dislodge adsorbed vapors and gases.

To accomplish the desired end, sheet insulation 13, supplied from a suitable source, such as roll 14, is passed upwardly in the direction of the arrow and over suitable guide means 15 and then downwardly into the compound present in container 1. The hot compound vaporizes any moisture present in or on the insulation. In its travel the insulation is conducted downwardly through compound 4 to such depth that the hydrostatic pressure of the compound overcomes the surface tension of any bubbles of gas which may be entrapped within the insulation or adsorbed on its surface. Ordinarily a depth of 30 inches is sufficient. For some types of insulation, however, and especially with low winding speeds and good fluidity of the compound, depths of 27 inches or even 18 inches are entirely satisfactory, it being understood, however, that these figures are by way of example only and specifically, as such, form no part of my invention. The gases will escape upwardly to the atmosphere. To facilitate the free passage of the liberated gases it is desirable that the sheet insulation 13 pass downwardly into the compound in as nearly a vertical path as possible, so that when the gases pass upwardly, they will not contact either face of the

downwardly moving strip. To achieve this result, lower guide roller 16 is positioned almost immediately beneath guide 15.

Contact between strip 13 and the walls of container 1, and possible undue heating of insulation and consequent charring, is prevented by guide 18 mounted on the cooler upper-part of the container. Guide 18 and roller 16 maintain strip 13 an even, safe distance from the rear wall 10 of container 1.

After the insulation has passed down through the compound 4, it is directed by guide 16 upwardly and around a third guide, such as roller 17. From the roller 17, the strip 13 passes directly to the winding form 7. It is to be noted that the strip is maintained beneath the surface of the compound prior to the winding operation, as well as during that operation. A suitable knife or cutting means, not shown, is provided to cut the insulation after a desired amount has been wound onto the form. Other means, not shown, are provided for starting the insulation after the next layer of wire has been wound onto the form.

To ensure that the gases which are liberated from the paper will escape to the atmosphere without coming into the region of the form 7, I provide a partition, or baffle 19 of any convenient material, and extend the same down into the container approximately at least as far as the strip 13 extends, supporting this partition in any suitable manner, not shown. Conveniently, the partition 19 terminates short of the bottom of the container, and the strip 13, after passing downwardly, passes underneath the partition 19, and thence upwardly through what may be termed a main chamber 20 across the roller 17, but below the surface 3, to form 7. As suggested in the foregoing, the partition 19 separates the container 1 into what is known as a main chamber 20 and a smaller, degasifying and dehydrating chamber 21. To the end of ensuring the desired isolating action, that is, the prevention of escape of liberated gases to the form, the partition 19, as illustrated in Fig. 2, is made somewhat wider than the strip 13.

In winding a coil many turns of wire must be wound before a layer of wire is completed. Following this a single turn of paper 13 is required. Accordingly the paper 13 remains in the degasifying and dehydrating chamber, between the moment at which it is introduced into the compound and the time when it reaches the lowermost point in its travel, a time sufficient for the removal of all entrapped gases and all moisture. It is essential that at no time after the strip 13 and the wire 10 have been introduced into the compound 4, until they have been wound on form 7, will they be exposed to the atmosphere. Roller 17, baffle 19, and form 7 are relatively positioned to achieve this result.

While in the above, consideration is given to the winding of a single coil, it will be understood that my invention is adaptable to the winding of a plurality of coils simultaneously. In this embodiment, and having particular reference to Fig. 5, it is to be noted that an increase is made in the dimensions of the container 1 in order to accommodate the elongated form 22. Insulation strip 13 is of increased width as indicated. A plurality of wires or conductors 10 are lead into the container and wound onto the elongated core tube mounted on the winding form. In this way a plurality of coils 9 are built up on the form 22, with open spaces 23, filled only with insulating

compound 4 and layers of paper 13, interspaced therebetween. For example, in a typical case, the form 22, for the production of say 25 to 30 coils, may be around 45 to 50 inches long. While an elongated arbor 24 is shown, extending through the form and adapted to be journaled in suitable conventional manner in the container 1, it is obvious that this arbor may take any desired configuration, such for example as stub shafts at each end of the form. In this embodiment, as well as in those of the remaining figures, I have affixed the winding form or its spider, as the case may be, to the arbor by keying, although, of course, any other desirable means of securing the two elements together may be employed.

It is to be noted that since the strip 13 becomes thoroughly impregnated with the compound 4 before it is wound on the coil, and further since there are no gases in the compound or on the strip by the time the latter reaches the form 7, the ends or margins of the coils may be sealed or collapsed without the formation of gas pockets as ordinarily encountered in the prior art. A further feature of my invention, therefore, is the provision of means for clamping the ends of the winding form, thereby substantially sealing the marginal ends of the layers of the strip or insulation 13 built up thereon and preventing the leakage or drainage out of the ends of the coils of the compound 4, during the removal of the form from the container 1. The wound coil is then removed from the form after the compound has cooled and hardened. Although such clamping means may take any one of a plurality of different embodiments, and is applicable to the production of one coil, as well as a plurality, I have elected to show one such embodiment in Fig. 5. Arbor 24, shown as threaded at 25-25 adjacent to but just short of each end, is adapted to receive threaded clamping collars 26, 27. These are loose while in the compound 4, but are tightened, as by a wrench or the like, before the form is withdrawn from the container 1. These collars seal the ends of the coils. Preferably the width of the collars 26, 27 is greater than that of the coils 9.

After removal of form 22 from container 1, the core tube with its plurality of coils thereon is removed from the form. After the impregnating compound has solidified on the coils, then the tube is sawed, as along lines 28-28, to separate the several coils. The spaces 23 are of sufficient width to provide sparking margins of satisfactory length at the edges of the completed coils.

Certain desirable results are achieved in coil production employing a modified form of container, as indicated in Figure 3. A container 29 is provided, filled with the compound 4 to the level 3. In the container 29 is housed a rotatable arbor 30, on which is mounted, as by keying, a winding form 31, similar to the form 7 of Fig. 1. On this form there is mounted a core tube 32, the coil 33 being wound on this tube 32 from wire 10 and paper or other flexible sheet insulation 13, all movements being in the direction of the arrows. A supply roll 14 is provided, along with rollers 15, 16, and 17, as in the embodiment of Fig. 1.

Heating of the container 29 is accomplished by means of heating chamber 34 provided between the container and the wall 34a substantially surrounding it. Wall 34a is formed of suitable metal or of insulating material, as found desirable. In

order to ensure uniform heating of container 29, and hence of the compound 4, and to eliminate local hot spots with consequent partial decomposition of compound, insulation 13, or the insulation on the wire 10, I distribute uniformly about the chamber 34 a plurality of electrical heating elements 35. These preferably are of substantially the same electrical rating. It is to be understood, however, that I am by no means committed to the use of electrical heating means to the exclusion of all others, and when I find it desirable to so do, I contemplate the use of the chamber 34 as a chest for steam or hot gases, with suitable modification in such case for the provision of inlet and outlet.

In the embodiment illustrated in Figure 3, the partition 36, dividing the interior of the container into a degasifying and dehydrating chamber 37 and a main chamber 38, extends to or adjacent the bottom of the container 29, and stops short of the surface of the compound. The arrangement of the rollers 16 and 17 is such that the strip 13 passes both downwardly and upwardly through the degasifying and dehydrating chamber. Any given element of the strip 13 remains in the chamber 37 during the entire time that a layer of wire 10 (constituting a large number of turns of wire) is being wound on the coil, hence, there is ample time for the removal of all moisture and gas during the down and up travel of the strip 13 through the chamber. Since the strip travels substantially vertically through chamber 37, it offers substantially no impedance to the flow of liberated gases up through the chamber.

A further modified form of my apparatus is indicated in Figure 4. In this modification the container 39, as distinguished from the containers 1 and 29 of Figures 1 and 3, respectively, is of just sufficient size to house the winding form assembly comfortably but comparatively snugly, with sufficient room to receive an adequate supply of compound 4 up to level 3. This container provides what I choose to describe as a main chamber 40. A well 41, the walls of which are of metal or insulating material, depending upon choice, provides an elongated degasifying and dehydrating space 42, of length sufficient to ensure that the hydrostatic pressure of the head of the compound is sufficient to overcome bubbles of gas entrapped on the fibrous insulation 13 passing through the compound. Well 41 conveniently is disposed laterally of the container 39 and opens into 39 at a junction point 43 well below the surface of the compound. Thus the compound will flow over from the container 39, filling the well 41 to the same level as that maintained in container 39. To ensure that gases liberated in the well 41 and escaping to the surface do not migrate into the vicinity of the form 31, a baffle or partition 44 is built up from the junction 43 of the container 39 and well 41. Baffle 44 extends to a point just short of the surface of the compound, thus effectively increasing the height of the degasifying and dehydrating chamber 42. It is to be particularly noted that locations of roller 17, baffle 44, and the winding form 31 are such that at no time after strip 13 and wire 10 have been introduced into the compound 4 will these two elements be exposed to the atmosphere until the coil is completely wound.

Shown as surrounding the container 39 and well 41 is a heat insulating jacket 45, conveniently of metal or insulating material, and forming, together with the container 39 and well 41, a

continuous heat chamber 46. Where desired this chamber may be made discontinuous, as for example by having a first heat chamber about the container 39, and a second, separate heat chamber about the well 41. While I contemplate the use of any suitable fluid heating medium in the chamber 46, such as hot gases or steam, I have elected to show for this purpose a plurality of electrical heating coils 47, all conveniently of substantially the same electrical rating. These heating coils are disposed substantially uniformly in the chamber 46 about the container 39 and well 41.

A construction such as that illustrated in Figure 4 is characterized by its economy in material and the amount of compound required, and by the space necessary for housing the assemblage.

Experience shows that coils wound in accordance with my invention and of equal current-carrying capacity as prior art coils, are of substantially smaller depth, which means smaller distance between layers of wire. The leakage reactance of these coils is appreciably less than those of the prior art. This construction permits more efficient operation. The compactness of the coil also tends to increase the rate of dissipating heat from its interior. This feature permits safer operation.

As a further point the distributed capacity of my coils is greater than those of the like ratings of the prior art. In fact, the distributed capacity may be sufficiently high as compared to the inductance as to prevent harmful oscillations and excessive potentials being reached, potentials which frequently are of such values as to rupture the insulation.

Thus it will be seen that there has been provided in this invention an art and apparatus for producing induction coils in which the various objects hereinbefore noted, together with many thoroughly practical advantages, are successfully achieved. It will be seen that the apparatus and method are simple, economical and efficient and that the resultant coil is rugged and compact in construction and well adapted to withstand the many varying conditions encountered in actual use.

While, as illustrative of my invention, certain embodiments have been described, it will be understood that satisfactory coils are produced so long as the entrapped gases and moisture on the sheet insulation and wire are removed by a fusible compound. This result is achieved by immersing these materials in a fusible compound at a temperature above the boiling point of water at such pressure as to free them of adsorbed gases and vapors and then bringing them in moisture and gas-free condition to the winding form. The coils are wound within the compound and are so removed that the fused compound is prevented from escaping during the cooling and hardening thereof.

It will, furthermore, be understood that although heating means preferably are provided for the insulating compound, I can eliminate this heating of the impregnating compound where the same is liquid at the working temperature and is preliminarily hydrofuged to free it of moisture, and where the paper and wire are pretreated to remove substantially all moisture normally present in these materials.

Likewise, it will be understood that in certain cases, vacuum conditions may be maintained in connection with the containers of the various embodiments. The use of a vacuum facilitates

moisture and gas removal and in addition aids impregnation of the paper and layers with the insulating compound.

Since many possible embodiments may be made of my invention and since many changes may be made in the embodiments hereinbefore set forth, it will be understood that all matter described herein, or shown in the accompanying drawing, is to be interpreted as illustrative, and not in a limiting sense.

I claim:

1. In the production of uniformly impregnated coils free of entrapped gas and moisture particularly adapted for high potential and high frequency electrical apparatus, the art which comprises, submerging a winding form in a fusible insulating and impregnating compound wholly beneath the surface thereof, passing flexible sheet insulation downwardly through the compound to a depth substantially greater than that of the form and then back up to the form to ensure that the hydrostatic pressure of the compound will remove substantially all bubbles of entrapped gases from the insulation, winding on the said form while in its submerged position desired layers of conducting wire and insulation, the wire and insulation being maintained continuously submerged in said compound from the time of their introduction until wound on the form, and heating the compound to a temperature somewhat above the boiling point of water in order to vaporize all moisture present in compound, wire and insulation.

2. In the production of uniformly impregnated coils free of entrapped gas and moisture particularly adapted for high potential and high frequency electrical apparatus, the art which comprises, submerging a winding form in a fusible insulating and impregnating compound, maintaining said compound at atmospheric pressure, passing conducting wire into said compound, passing flexible sheet insulation downwardly and substantially vertically into such compound to a greater depth than said winding form in order that entrapped gases on said insulation are driven off by the hydrostatic pressure, then passing the insulation upwardly to the winding form, winding said insulation and said wire, while submerged, in layers onto said form, and maintaining the compound at such temperature as to fuse the same and drive off all moisture on said insulation.

3. In the production of uniformly impregnated coils free of entrapped gas and moisture particularly adapted for high potential and high frequency electrical apparatus, the art which comprises, passing flexible sheet insulation downwardly through an insulating compound into a degasification and dehydration space a sufficient depth to ensure that the hydrostatic pressure of the compound will remove all bubbles of entrapped gases, then winding wire and the degasified and dried insulation onto a winding form maintained in submerged position in a main space separate from said degasification and dehydration space, said wire and insulation being maintained continuously submerged in said compound from the time of their introduction until wound on the form.

4. In the production of uniformly impregnated coils free of entrapped gas and moisture particularly adapted for high potential and high frequency electrical apparatus, the art which comprises, submerging a winding form in a fusible insulating and impregnating compound, passing

flexible sheet insulation downwardly through the compound a sufficient depth to ensure that the hydrostatic pressure of the compound will remove all bubbles of entrapped gases from the insulation, winding on said form while in its submerged position alternate layers of conducting wire and said sheet insulation, and compressing the ends of the formed coil while removing the coil from the compound, to prevent the compound from draining off before it hardens.

5. In the production of uniformly impregnated coils free of entrapped gas and moisture particularly adapted for high potential and high frequency electrical apparatus, the art which comprises, submerging a winding form and a coil tube for a plurality of coils in a fusible insulating and impregnating compound, passing flexible sheet insulation downwardly through the compound a sufficient depth to ensure that the hydrostatic pressure of the compound will remove all bubbles of entrapped gases from the insulation, winding on said tube while in its submerged position, in such manner as to form a plurality of separate coils alternate layers of conducting wire and said flexible sheet insulation, and compressing the ends of the tube with covering members while removing the same from the compound, to prevent the compound from draining off before it hardens.

6. In apparatus of the character described, coil winding apparatus comprising, in combination, a container adapted to be filled with fusible insulating and impregnating compound and including a degasification and dehydrating chamber, a source for supplying flexible sheet insulation, a winding form rotatably mounted in said main chamber below the normal level of the compound therein, means for passing the insulation from said source to said form downwardly into the degasification and dehydration chamber a sufficient distance under the surface of the compound to drive off gases entrapped on the insulation, and means for passing conducting wire into said compound to the form, so that alternate layers of insulation and wire may be built up on said form underneath the surface of said compound.

7. In apparatus of the character described, coil winding apparatus comprising, in combination, a container adapted to be filled with fusible insulating and impregnating compound, means separating the interior of the container at least partially into a degasifying and dehydrating chamber and a main chamber, a source for supplying flexible sheet insulation, a winding form rotatably mounted in said main chamber below the normal level of the compound therein, means for passing the insulation from said source downwardly and substantially vertically into the degasifying and dehydrating chamber a sufficient depth under the surface of the compound to drive off gases entrapped on the insulation, the liberated gases passing freely upwardly in said degasifying chamber, means passing the insulation to the winding form, and means for passing conducting wire into said compound to the form so that alternate layers of insulation and wire may be built up on said form underneath the surface of said compound.

8. In apparatus of the character described, coil winding apparatus comprising, in combination, a container adapted to be filled with fusible insulating and impregnating compound, means for uniformly heating the container, means separating the interior of the container at least partially

into a degasifying and dehydrating chamber and a main chamber, a source for supplying flexible sheet insulation, a winding form rotatably mounted in said main chamber below the normal level of the compound therein, means for passing the insulation from said source to said form downwardly into the degasifying and dehydrating chamber a sufficient depth under the surface of the compound to drive off gases entrapped on the insulation and thence while still submerged into the main chamber to said form, and means for passing conducting wire into said compound to the form so that alternate layers of insulation and wire may be built up on said form underneath the surface of said compound.

9. In apparatus of the character described, coil winding apparatus comprising, in combination, a container adapted to be filled with fusible insulating and impregnating compound, a source for supplying flexible sheet insulation, a partition in said chamber terminating short of the bottom of the latter and separating the interior thereof into a degasifying and dehydrating chamber and a main chamber, said partition being wider than the width of the sheet insulation, a winding form rotatably mounted in said main chamber below the normal level of the compound therein, means for passing the insulation from said source downwardly into the degasifying and dehydrating chamber and thence underneath the partition and directly up to the form, and means for passing conducting wire into said compound to the form, so that alternate layers of insulation and wire may be built up on said form underneath the surface of the compound.

10. In apparatus of the character described, coil winding apparatus comprising, in combination, a container adapted to be filled with fusible insulating and impregnating compound, a source for supplying flexible sheet insulation, a partition in said chamber terminating short of the normal surface of the compound and separating the interior of the container into a degasifying and dehydrating chamber and a main chamber, a winding form rotatably mounted in the main chamber below the normal level of the compound therein, means for passing the insulation from said source downwardly into the degasifying and dehydrating chamber a sufficient depth under the surface of the compound to drive off gases entrapped on the insulation, and thence back upwardly through the degasifying and dehydrating chamber and across the top of the partition, under the surface of the compound, to the winding form, and means for passing conducting wire into said compound to the form, so that alternate layers of insulation and wire may be built up on the form underneath the surface of the compound.

11. In apparatus of the character described, coil winding apparatus comprising, in combination, a container adapted to be filled with fusible insulating and impregnating compound, a winding form rotatably mounted in said container below the normal level of the compound therein, an elongated well comprising a degasifying and dehydrating chamber disposed laterally of said container and opening at its top into said container below the normal level of the compound, a source for supplying flexible sheet insulation, means for passing the insulation from said source downwardly into the degasifying and dehydrating chamber a sufficient depth under the surface of the compound to drive off gases entrapped on the insulation, and thence back through the de-

gasifying and dehydrating chamber and over into the container, under the surface of the compound, to the winding form, and means for passing conducting wire into said compound to the form, so that alternate layers of insulation and wire may be built up on the form underneath the surface of said compound.

12. In apparatus of the character described, coil winding apparatus comprising, in combination, a container adapted to be filled with fusible insulating and impregnating compound, means for heating the container, means separating the interior of the container at least partially into a degasifying and dehydrating chamber and a main chamber, a source for supplying flexible sheet insulation, an elongated winding form, on which a plurality of separate coils can be wound simultaneously, an arbor extending through said form and beyond the ends thereof and journaled in the main chamber of said container in such manner that the form will be disposed below the normal level of the compound in the chamber, means for passing the insulation from the said source downwardly into the degasifying and dehydrating chamber a sufficient depth under the surface of the compound to drive off gases entrapped on the insulation and thence to the form,

means for passing a plurality of conducting wires into said compound to the form, so that alternate layers of insulation and wire will be built up on the form as separate coils underneath the surface of the compound, and means for clamping the ends of the form to prevent draining of the hot compound before it cools and solidifies when the form is removed from the container.

13. In the production of uniformly impregnated coils free of entrapped gas and moisture particularly adapted for high potential and high frequency electrical apparatus, the art which comprises, submerging a winding form in a fusible insulating and impregnating compound, passing conducting wire into the compound to said winding form, passing flexible sheet insulation spaced from said wire downwardly and substantially vertically into such compound to a greater depth than said winding form in order that entrapped gases on said insulation are driven off by the hydrostatic pressure, then guiding said submerged insulation to the winding form, winding said insulation and said wire, while submerged, in layers on said form, and maintaining the compound at a temperature so as to fuse the same and drive off all moisture on said insulation.

CHARLES PHILIPPE BOUCHER.
